CLAIM

The ornamental design for a dryer ball, as shown and described.

DESCRIPTION

FIG. 1 is a perspective view of an embodiment of a dryer ball, in accordance with the design;

FIG. 2 is front view of the dryer ball of FIG. 1;

FIG. 3 is a right-side view of the dryer ball of FIG. 1;

FIG. 4 is a rear view of the dryer ball of FIG. 1;

FIG. 5 is a left-side view of the dryer ball of FIG. 1;

FIG. 6 is a top view of the dryer ball of FIG. 1; and,

FIG. 7 is a bottom view of the dryer ball of FIG. 1.

Broken lines in the drawing depict environmental structure or boundaries that form no part of the design to be patented.
